UNITED STATES PATENT OFFICE.

ALWIN H. BECK AND EDWIN S. MIX, OF ROCHESTER, NEW YORK, ASSIGNEES TO HICKOK MANUFACTURING COMPANY, INC., OF ROCHESTER, NEW YORK, A CORPORATION OF NEW YORK.

DETACHABLE LINK.

Application filed July 22, 1926. Serial No. 124,250.

The present invention relates to detachable links and an object of the invention is to provide a strong and durable structure through which a flexible connection such as a watch chain may be detachably and effectively connected to any suitable article, such, for instance, as a watch. A further object of the invention is to provide a link which will connect with the article in such a manner that pulling or twisting strains on the link will not effect the disconnection of the article from the link. Still another and further object of the invention is to provide a link structure which may be economically manufactured due to the fact that the number of parts entering into the same are reduced to a minimum.

To these and other ends, the invention consists of certain parts and combinations of parts, all of which will be hereinafter described: the novel features being pointed out in the appended claims.

In the drawings:

Fig. 1 is an end view of the link;

Fig. 2 is a side view of the link closed;

Fig. 3 is a side view of the link open;

Fig. 4 is a section on the line 4—4, Fig. 3;

Fig. 5 is an edge view of the link;

Fig. 6 is a section on the line 6—6, Fig.

2; and

Fig. 7 is a perspective view showing another way in which the closure member of the link may be constructed.

In the illustrated embodiments of the invention, there is employed a body member 1 preferably formed from a flat metal stamping, thus making it possible to obtain greater strength in the walls of the link due to the fact that the grain structure of the material produced in the rolling operation of the flat metal extends in a direction to resist the pulling strain on the link. This body member 1 in this instance has a large elongated opening 2 which extends throughout a greater portion of the body, the sides of the opening gradually flaring from one end of the body toward the opposite end throughout the greater portion of the opening, and then converging at greater angles than the main portions of the sides of the opening. The body may also be provided at one end with an opening 3 through which a flexible connection may be secured to the link, such, for instance, as a watch chain. The elongated opening 2 has a throat opening 4

through one of the sides thereof and by this opening the swinging link of a watch or any other suitable device, may be passed into the opening 2 so as to surround the body of the link below the opening. 60

In order to effect the closure of the throat 4, a closure member is provided. This closure member is mounted to turn on the body member on that side of the elongated opening 2 opposite the throat 4. In this instance, the body is reduced at 5 to provide a bearing and shoulders 6 at opposite ends of the bearing. The closure 7 which in this instance is formed from sheet metal, has a sleeve 8 carried thereby and preferably formed by rolling the metal of the closure into tubular shape, this sleeve being passed about the bearing 5 so that the closure may swing transversely of the plane of the link on said bearing toward and from closed position. 70 The closure, when in closed position, extends from the bearing across the opening 2 and bridges the space between the sides of the throat 4 so that when in closed position it restricts the size of the opening 2 to an area 80 sufficient for receiving the link of the watch or other article passed through the opening 2.

With the end in view of locking the closure against accidental displacement in closed position, there is projected from each wall of the throat 4 a projection 9, these projections extending toward each other. The closure has two openings formed on opposite sides of its swinging end for receiving these projections, there being provided 90 in the link or in the closure, or both, sufficient resiliency to permit a relative movement between the projections 9 and the walls of the openings in which said projections are received. 95

In the embodiment of the invention shown in Figs. 1 to 6 inclusive, the closure is recessed at 10 at its free end and the free end is rolled so as to provide two tubes 11 aligned with each other, the outer ends of these tubes forming the openings in which the projections 9 are received. In order to limit the movement of the closure to swing to one side of the link only the ends of these tubes may be formed so as to provide projections or stops 12 on one side which will cooperate with the body of the link adjacent the throat 4 and prevent the movement of the closure entirely through the throat. In this embodiment, a cross section of the clo- 110

sure is substantially $\S$ shaped, the bearing tube being turned from the metal in one direction and the tube 11 being turned from the metal in the opposite direction, as clearly indicated in Fig. 1 of the drawing.

The form of the closure shown in Fig. 7 is also formed from sheet metal. This closure 7^a has, however, the bearing tube 8^a rolled on that side of the metal on which the tube 11^a is rolled. In this instance, the closure member is not slotted at its swinging end although it might be, and only one tube is formed, the opposite ends of which form openings for receiving the projections 9 of the body member. It has been found that the metal of the body member has a certain resiliency which will permit the ends of the tube 11^a to ride on and off the projections 9, and specially when the latter are bevelled as shown in the drawing. It has been further found, however, that the projections 9 may be made longer, if in addition to the resiliency present in the body member, a resilient connection is provided between those two portions of the closure in which are formed the openings for receiving the projections 9.

From the foregoing it will be seen that there has been provided a detachable link formed from only two parts without the employment of a separate spring. The link body has an opening provided with a lateral throat which is adapted to be opened and closed by a closure member swinging transversely of the plane of the body preferably on the body at that side of the opening opposite the side in which the throat is provided. This closure member is provided with portions on opposite sides thereof which interlock with the walls of the throat of the opening, one or both of said parts being resilient so as to permit the interlocking. Stops are provided preferably on the closure to limit the movement of the closure to swinging in one direction toward and from the throat.

What we claim as our invention and desire to secure by Letters Patent is:

1. A detachable link comprising a body member formed with an opening and throat leading from one side of the opening, a closure for the throat mounted to swing on the body about an axis extending longitudinally of the link on that side of the opening opposite the throat, and interlocking means ar-

ranged on opposite walls of the throat and the opposite sides of the closure for holding the closure in a closed position, said interlocking means comprising rigid projections on the walls of the throat and openings in opposite sides of the closure in which the projections are adapted to enter.

2. A detachable link comprising a body having an opening formed with a throat in one side thereof, the walls of which are rigid, the body having on the side of the opening opposite the throat a bearing, and a closure member having tubular portions surrounding said bearing to turn therein, and having a portion arranged to close the throat said portion having openings in opposite sides to receive the rigid walls of the throat.

3. A detachable link comprising a body having an opening provided with a throat on one side thereof, and a closure formed from sheet metal rolled at one side to provide a bearing mounted on the body on that side of the opening opposite the throat and rolled at the opposite side to provide two openings at opposite sides of the closure, and rigid projections on the walls of the throat for entering said openings of the closure.

4. A detachable link comprising a body having an opening provided with a throat at one side thereof, a closure for the throat mounted to turn on the body on that side of the opening opposite the throat, said closure having two resiliently mounted portions each provided with an opening, said openings being arranged on opposite sides of the closure, and rigid projections on the walls of the throat for entering said openings.

5. A detachable link comprising a body having an opening provided with a throat at one side thereof, the walls of the throat being rigid, a closure for the throat mounted on the body about an axis extending longitudinally of the link on that side of the opening opposite the throat, said closure having openings in opposite sides to receive the rigid walls of the throat, the closure being provided with portions projecting at one side of each opening to form stops in order to limit the movement of the closure in the throat.
